UNITED STATES PATENT OFFICE.

ALBERT LINDSAY DOERING, OF GERMANTOWN, PENNSYLVANIA, ASSIGNOR TO J. S. THORN COMPANY, OF PHILADELPHIA, PENNSYLVANIA, A CORPORATION OF PENNSYLVANIA.

SASH FRAME.

Application filed January 19, 1923. Serial No. 613,664.

My invention is particularly applicable to metallic frames in which the sashes are tilt-able upon horizontal pivots and used as ventilators. Such frames are provided with 5 members termed "weathering" sections which are in fact channels so disposed as to shed rain which otherwise might find access between the relatively movable members of the frame.

10 As heretofore constructed; the pivots of such sashes extend through holes punched in flat hinge plates, at right angles to the plane of the latter, which plates extend from the respective weathering sections parallel and 15 in contact with each other in planes at right angles to the plane of the glass in the sash frame. That is to say; such ordinary construction, at each joint, includes a tilt-able muntin bar, member of the sash which is 20 to be tilted, a stationary muntin, member of the stationary frame in which said sash tilts, and a pair of plane hinge plates respectively rigidly connected to said tilt-able and stationary muntin bars and projecting 25 extensively from the sash frame in a plane transverse to the axis upon which the sash tilts.

Such sash frames have been found objectionable because when stacked for transportation, the weight of the frames and stresses to which they are subjected, are concentrated upon said projecting plane hinge plates; so that the effect of transportation, or even of ordinary handling 30 incident to building construction, is to so far deform such ordinary hinge members, relatively to their respective sash frames, that they must be repaired before they can be used.

40 Therefore, the principal object and effect of my present invention are to avoid the use of such projecting plane hinge members; substitute for the same tubular hinge bearings which are rigidly connected in unitary 45 and close relation with the respective sash frame weathering sections, and thus render the construction more rigid and compact and avoid the deformation and damages and costly repairs which are necessitated by the 50 use of the ordinary construction aforesaid.

My invention includes the various novel features of construction and arrangement hereinafter more definitely specified.

In said drawings; Fig. I is a fragmentary

edge elevation of a sash frame embodying 55 my invention; the outer face of said frame being at the left hand side of said figure.

Fig. II is a fragmentary horizontal sectional view of a portion of said sash frame, taken on the line II, II in Figs. I and III. 60

Fig. III is an interior elevation of the frame members shown in section in Fig. II.

Fig. IV is a fragmentary edge elevation of a sash frame, similar to Fig. I, but showing a modified form of my invention. 65

Fig. V is a fragmentary horizontal sectional view of a portion of said sash frame shown in Fig. IV; taken on the line V, V in Figs. IV and VI.

Fig. VI is an interior elevation of the 70 frame members shown in section in Fig. V.

Fig. VII is a vertical sectional view similar to Fig. I, but showing the entire window structure.

In said figures; the stationary sash frame 75 1 includes the vertical muntin bar 2 and frames the plate of glass 3 secured therein by the putty or other cement 4. The tilt-able sash 6 includes the vertical muntin bar 7, 80 which is precisely like said bar 2, and forms a frame for the plate of glass 8 which is secured therein by the putty or other cement 9. The two weathering sections 10, one of 85 which is shown in section and the other indicated in elevation in Fig. II, are precisely alike but oppositely disposed, as indicated in Fig. III. Said sections 10 are respectively rigidly connected with said muntin bars 2 and 7, conveniently by the rivets 12 and 13 indicated in Figs. I and III. 90

Each of said weathering sections 10 is normally of the configuration shown in cross section in Fig. II, to wit, it is a channel bar having parallel flanges connected by a web in unitary relation therewith, but said flanges are of different widths; the narrow flange 15 extending between said muntin bars 2 and 7 to cover the interstice between them, and the wider flange 16 overlapping the muntin bar 2 to which it is not attached, so that each of said weathering strips overlaps two joints between the relatively movable members of the frame. 100

In accordance with my invention, such weathering sections 10 are cut and bent at their ends to the cylindrical tubular configuration shown, so as to form from the metal of the wider flange 16 thereof, a tubular

hinge bearing 17 extending parallel to the normal plane of the frame, i. e., parallel with the common plane of said glass panels 3 and 8; so that when similar weathering sections 10 are disposed in opposite relation as shown, a pintle 18 may be fitted through the axially alined openings 19 therein. I find it convenient to form said pintle as a rivet having heads 20, at its opposite ends, respectively bearing upon the respective weathering sections 10 which it thus pivotally connects and holds together in the operative assembled relation shown.

It may be observed that the construction and arrangement above described are such that said weathering sections 10 not only perform the function of sealing the joints between the relatively movable members of the sash frame, but also serve as hinge members 20 without the addition of any other elements.

In the form of my invention shown in Figs. I to III inclusive; the ends 21 of said sections 10 are first bent outwardly at 23 and then curled inwardly toward the frame, to 25 form the respective tubular hinge bearings 17; so that said cut ends 21 are not visible at the inner face of the sash frame but are concealed. Therefore, I consider that construction and arrangement preferable. However, 30 it is simpler and less difficult to bend the cut ends of said weathering sections 10 in the opposite direction, as in the form of my invention shown in Figs. IV to VI inclusive; wherein the cut ends 25 are merely curled 35 outwardly so that the cut ends are visible at the inner side of the frame. However, that construction and arrangement avoid the necessity of bending said sections at 23 as in the other construction and arrangement 40 aforesaid.

As shown in Figs. I and IV; the stationary portion of the sash frame is set in a sill formed of bars 26, 27 and 28, the latter overlapping the building wall 29; said bars 45 being assembled so as to shed water away from the sash frame and said wall and afford a neat appearance. As shown in said Figs. I and IV; the tiltable part of said sash frame is provided with the top rail 31 having the flanges 32 and 34 fitting against the stationary sash rail formed by the two bars 35 and 36, which are assembled in rigid relation; said bar 36 having the drip flange 37 overhanging the flange 32 on the sash frame 50 so as to shed water away from the latter. However, sash frames embodying my invention 55 may be otherwise constructed and arranged.

Therefore, I do not desire to limit myself 60 to the precise details of construction and ar-

rangement herein set forth as it is obvious that various modifications may be made therein without departing from the essential features of my invention, as defined in the appended claims.

65

I claim:

1. A pivotal sash mounting comprising a wrought metal channel bar, having a plane web, provided with means for attaching it to a muntin bar, and two plane flanges extending at right angles to said web, one of said flanges being wider than the other, and a cylindrical tubular pintle bearing formed of the metal of said wider flange, curled outwardly, with the axis of said bearing parallel with the planes of said flanges and at right angles to the plane of said web; said bearing being of less axial extent than said wider flange and flush with the free edge of the latter.

70

2. A pivotal sash mounting comprising two counterpart interchangeable sections each constructed and arranged as described in claim 1; the pintle bearings being axially alined, with the free edges of the flanges upon which they are formed respectively turned outwardly in opposite directions; and a pintle extending through said bearings and hingedly connecting them; said pintle being permanently retained in said bearings 85 by means at the opposite ends of said pintle and carried by the latter; whereby said channel bars extend in parallel, but relatively offset, relation with respect to each other, from said pintle, with the narrower flanges thereof forming a continuous, plane, weathering surface.

90

3. A pivotal sash mounting including two interchangeable sections which are precisely alike and each comprising a channel bar having flanges of respectively different widths, respectively adapted to serve as weathering strips respectively at the side edge of the sash and the frame in which it is mounted; each of said bars having its wider flange 100 curled to form a cylindrical tubular pintle bearing in unitary relation therewith; and a pintle arranged as a rivet extending through said bearings with its axis parallel with the general plane of the sash and holding said bearings in coaxial relation and arranged to present said flanges upon the respective bars in plane alinement to form continuous plane weathering surfaces and with their ends abutting adjoining said pintle.

105

In testimony whereof, I have hereunto signed my name at Philadelphia, Pennsylvania, this 16th day of December, 1922.
